US0D1083802S

(12) **United States Design Patent** (10) Patent No.: **US D1,083,802 S**
(45) Date of Patent: ** Jul. 15, 2025

(54) **EARPIECE CHARGING CASE WITH
WINDOW**

(71) Applicant: **New Audio LLC**, New York, NY (US)

(72) Inventors: **Drew Stone Briggs**, Seattle, WA (US);
Nicholas Slaney, Jersey City, NJ (US);
Thomas C. Wilson, Brooklyn, NY
(US); **Marten Wallby**, Malmo (SE);
Jonathan E. Levine, New York, NY
(US)

(73) Assignee: **NEW AUDIO LLC**, New York, NY
(US)

(**) Term: **15 Years**

(21) Appl. No.: **29/853,241**

(22) Filed: **Sep. 14, 2022**

(57) **CLAIM**

The ornamental design for an earpiece charging case with window, as shown and described.

DESCRIPTION

FIG. 1 is a perspective view of an earpiece charging case showing our new design, as viewed from the top and front with the charging case in an open state.

FIG. 2 is a front elevational view thereof.

FIG. 3 is a back elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines depict portions of the earpiece charging case with window that form no part of the claimed design.

1 Claim, 4 Drawing Sheets
